Patented Oct. 24, 1922.

INVENTOR.

GOLIARD F. SHAFER

Ray Frey

ATTORNEY.

UNITED STATES PATENT OFFICE.

GALIARD F. SHAFFER, OF DETROIT, MICHIGAN.

SAFETY LIGHTING ATTACHMENT FOR GAS BURNERS.

Application filed April 30, 1921. Serial No. 465,717.

To all whom it may concern:

Be it known that I, GALIARD F. SHAFFER, a citizen of the United States, and residing at Detroit, county of Wayne, and State of Michigan, have invented a new and Improved Safety Lighting Attachment for Gas Burners, of which the following is a specification.

This invention relates to an improved safety lighting attachment for gas burners of both illuminating and heating types, and has for its primary object the arrangement of a constantly burning lamp supported in proximity to the mouth of a gas jet so as to 10 ignite any gas that issues therefrom. A further object of my invention is to provide a lamp that may be readily clamped upon a portion of the gas fixture adjacent to the burner and having one or more curved wick-carrying nozzles rotatable for adjustment 15 to position the flames directly above the burners.

A further object of my invention is to construct a lamp that will continue to burn as 20 long as any fuel oil remains in the tank and which is simple, durable, light and comparatively inexpensive to manufacture.

The above and other objects will be apparent from the following description 25 wherein reference is had to the accompanying drawing showing preferred embodiments of the invention and wherein similar reference numerals designate similar parts throughout the several views.

30 In the drawings:—

Fig. 1 is a side elevation of an illuminating gas burner and lamp in position for use;

Fig. 2 is a vertical section through the improved lamp;

Fig. 3 is a detail sectional view taken substantially on the line 3—3 of Fig. 1; and

Fig. 4 is a plan view of a gas stove and lamp in position for igniting any of the burners.

45 Referring now to the drawings the numeral 5 designates a burner of the ordinary illuminating type supported upon a pipe 6 projecting from a wall 7 of a room. The burner 5 may carry an incandescent mantle

50 of the usual type or may illuminate by burning the gas directly issuing from a jet. It is well known that if illuminating gas

escapes through such burner or jet in sufficiently large quantities it might asphyxiate any persons in the room, and at times the 55 escaping gas has continued sufficiently long to inundate an entire apartment or house. Even though the leak is discovered before fatalities occur the danger of a serious fire through the accidental or careless lighting 60 of a match, etc., is ever present. A less serious but annoying consequence of such leakage is the cost thereof to the householder who discovers a small leak only after a bill that seems unreasonable has been rendered 65 after the passage of several weeks.

My invention aims to prevent fatalities, serious fires and the like by providing a constantly burning lamp adjacent the jet of the burner 5 so as to ignite any gas issuing 70 therefrom, thereby utilizing the gas at the burner instead of permitting it to escape into the room. This provides safety in the use of gas for illumination even though carelessness or accident allows the gas to 75 issue from the jet at times when the burner is not desired for illumination. To this end I have shown in Fig. 1 a preferred embodiment of my invention comprising a tank 8 secured upon the pipe 6 of the burner 5 by 80 means of a clamp 9 or like suitable means, and provided with a wick-carrying nozzle 10 which may be adjusted to project directly above the jet from which the gas issues. By maintaining a flame at the end of the 85 nozzle 10 the ignition of gas issuing from the jet is assured.

The lamp whereby I obtain a constant flame at the end of the nozzle 10 is best shown in Fig. 2 and includes a tubular wick 90 11 extending through the nozzle 10 and the entire length of the tank 8, the wick being supported upon a central metallic wire or tube 12 resting at its lower extremity upon the bottom of the tank and projecting 95 through the upper end of the tank into the nozzle 10. To provide for the passage of the wick and metallic tube 12 through the upper end of the tank 8 and to provide a bearing for the adjustment of the nozzle 10 100 the upper end of the tank 8 is formed with a threaded apertured seat 13 for the reception of a nut 14 having an internal tapering wall 15 adjacent its upper extremity adapt-

ed to rest upon the flaring lower extremity 16 of the nozzle (see Fig. 2 and co-operates therewith to clamp the nozzle against the upper extremity of the seat 13 to render the junction gas-tight. The central tube 12 and the wick 11 pass through the seat 13 into the nozzle 10 and extend a slight distance beyond the free end of the nozzle where it is ignited in the usual manner. Adjacent 10 the free end of the nozzle I have provided a cut out portion 17 through which the wick may be adjusted as desired. When the wick is being inserted into the nozzle it is also fed along by grasping it through the cut 15 out 17.

The nozzle 10 may be of any desired shape and length, one shape being illustrated in Fig. 2 and another in Fig. 4, by way of example, it being essential merely that the nozzle project from the tank 8 into proximity to the jet from which the gas issues. In Fig. 2 I have shown a single curved nozzle which is mounted to rotate about the seat 13, the 20 nut 14 being loosened when it is desired to adjust the position of the nozzle, the nozzle being then moved to the desired new position and the nut being then tightened to again hold the nozzle.

30 In Fig. 4 I have shown a slightly modified form of my invention which comprises a plurality of nozzles 10^a projecting from the tank 8^a into proximity to the burners 5^a of a gas stove. These nozzles 10^a are separately adjustable to any desired position, each carrying a tubular wick and central supporting metallic tube or wire substantially as described above. In this form of 35 my device I have shown the tank 8^a clamped to the feed pipe 18 which supplies all the burners with fuel, this pipe being positioned at the front of the stove in the ordinary manner, and the clamp 9^a for securing the tank thereto being fixed to the 40 bottom of the tank. If desired the tank could be held to a pipe or other portion of a gas fixture by means of a side clamp 19 (shown in dotted lines in Fig. 2) and adapted to be secured to the tank by means 45 of a bolt 20 soldered or otherwise fixed into the side of the tank, the clamp 19 being firmly held between the side of the tank and a nut 21 threaded upon such bolt.

The tank is filled through an opening 22 50 substantially as shown in Fig. 2, so that the opening projects upwardly when either bottom clamp 9 or side clamp 19 are utilized for holding the tank upon the gas fixture. A suitable cap 23 closes the opening when 55 the tank is filled. I preferably use a mixture of kerosene and lard oil for filling the tank, prepared by melting lard and pouring the liquid so formed into the tank on top of the kerosene with which it mixes while heated. It will be noted that as long as the

gas burner is lighted the tank 8 is heated because of its position adjacent the burner, and this heat keeps the mixture of lard oil and kerosene in readiness for vaporization by means of the wick in the ordinary manner. It is to be understood that my invention is not limited to the use of such a mixture of lard oil and kerosene, as I contemplate the use of calcium carbide or any other desirable medium for maintaining a 70 fuel supply for the flame of the lamp. I have, however, had success in burning the mixture above described and prefer its use. 75

To indicate the quantity of liquid contained in the tank I provide a gauge 24 of 80 any desired construction, the one illustrated consisting of a float 25 carrying a projecting rod and from the length of the projecting portion of the rod the relative content of the tank may be readily determined. 85

While it will be apparent that the illustrated embodiments of my invention herein disclosed are well calculated to adequately fulfill the objects and advantages primarily stated, it is to be understood that the invention is susceptible to variation, modification and change within the spirit and scope 90 of the subjoined claims.

Having described my invention I claim:—

1. A safety lighting attachment for gas 95 burners comprising an oil burning lamp supported upon a portion of the gas fixture, and having a curved wick-carrying nozzle rotatable about the body portion of the lamp to project the flame directly above the 100 burner.

2. A safety lighting attachment for gas burners of the multiple type comprising a lamp adapted to be supported upon a portion of the gas fixture and having a plurality of 105 wick-carrying nozzles rotatable to project the flames into proximity with the several burners.

3. A safety lighting attachment for gas burners of the multiple type comprising a 110 lamp adapted to be supported upon a portion of the gas fixture and having a plurality of wick-carrying nozzles independently adjustable to project the flames into proximity with the several burners. 115

4. A safety lighting attachment for gas burners comprising an oil burning lamp having a tank and a curved nozzle rotatably mounted thereon, a tubular wick extending through said nozzle and tank, and a central 120 supporting member extending through the wick for its entire length.

5. A safety lighting attachment for gas burners comprising an oil burning lamp and a rotatable nozzle and means for securing same either vertically or horizontally upon a gas fixture comprising clamps secured to the bottom and side of the lamp. 125

6. A safety lighting attachment for gas burners comprising an oil burning lamp 130

having a tank having a threaded projection thereon, a curved rotatable nozzle having its base in alignment with said projection, a nut threaded upon said projection and adapted to hold the nozzle in operative position thereon, a plurality of clamps mounted respectively on the bottom and side of said tank for securing the tank in vertical or

horizontal position, and a filling opening for the tank arranged so as to be on the upper portion of the tank when arranged in either vertical or horizontal position.
